United States Patent Office

Des. 182,194
Patented Feb. 25, 1958

182,194

TAPE RECORDER CASE OR SIMILAR ARTICLE

Harris E. Nelson, Evanston, Ill., assignor to Bell & Howell Company, Chicago, Ill., a corporation of Illinois

Application May 29, 1957, Serial No. 46,412

Term of patent 14 years

(Cl. D26—14)

FIG. 1.

Figure 1 is a perspective view of a tape recorder case or similar article embodying my new design; and

I claim:

The ornamental design for a tape recorder case or similar article, as shown.
